COIL-WINDING HEAD

Noble E. Moore and George R. Gillgrass, Davenport, Iowa, assignors of one-third to Lyster L. Brunson, Davenport, Iowa

Application March 12, 1945, Serial No. 582,398

5 Claims. (Cl. 140—92.2)

1

The present invention relates to the art of winding coils for stators of single phase motors and more especially to an improved apparatus for this purpose.

Among the objects of this invention are to provide a winding head on which coils of the type stated can be more quickly wound than upon heads of the prior art; to provide a head of the type indicated which can be readily collapsed for the removal of coils which have been wound and then re-set for winding other coils of the same diameter with a minimum consumption of time and labor; to provide a head of the type stated which will be readily adjustable after it has been collapsed to remove a coil therefrom; and such further objects, advantages, and capabilities as will hereafter appear and as are inherent in the structure disclosed herein. Our invention further resides in the combination, construction, and arrangement of parts illustrated in the accompanying drawings and, while we have shown therein what is now regarded as the preferred embodiment of this invention, we desire the same to be regarded as illustrative only and not to be interpreted in a limiting sense.

In the drawings annexed hereto and forming a part hereof,

Fig. 1 represents a side elevation of a coil winding head embodying our present invention;

Fig. 2 represents a cross-section of a part of a head taken substantially along the plane indicated by the line 2—2, Fig. 1;

Fig. 3 represents a fragmentary elevation looking at the left side of Fig. 1;

Fig. 4 represents a plan view of this construction, looking down on Fig. 1;

Fig. 5 represents a full elevation, looking at the left side of the structure shown in Fig. 1;

Fig. 6 represents an elevation of the unit shown in Fig. 2 looking in the opposite direction and with the parts in a different position of adjustment;

Fig. 7 represents an elevation of the smallest coil winding unit, the same being the lowest unit in Fig. 4;

Fig. 8 represents the same structure as Fig. 7 with the parts in a different position of adjustment;

Fig. 9 represents an enlarged section through the unit shown in Figs. 7 and 8 to show one mode of adjusting the arms to permit adjustment of the size of the coil wound thereon;

Fig. 10 represents an elevation of one unit of this construction;

2

Fig. 11 represents an elevation of the structure shown in Fig. 10 taken at a right angle to the plane of that figure;

Fig. 12 represents a side elevation of another unit of this construction; and

Fig. 13 represents a cross-section substantially along the plane indicated by the line 13—13, Fig. 1.

Reference will now be made in greater detail

10 to the annexed drawings for a more complete description of this invention. This invention relates to a mechanism for the winding of wire coils and comprises a plate 1 which has holes therethrough for the passage of bolts, screws or other fastening means by which it may be attached to a winding machine or other structure with which is to be used. To this plate 1 is fastened a post 2 which may be either integral with the plate or detachably secured thereto.

20 To the post 2 is secured a housing 3, which may be integral with the post, having a lever 4 pivotally mounted therein and secured to a shaft, on one end of which is mounted a cam 5. These constitute operable means for collapsing and expanding the winding head. Arcuate depressions 6 are formed in the proximate ends of the slides 7 and the points of the cam 5 turn in these arcuate depressions when the handle 4 is moved up or down.

25 This results in the slides 7 being forced apart or permitted to approach when the cam is turned. The ends of cam 5 may be provided with rollers for engagement with the concave ends of slides 7.

The parts 1, 2, 3, and 5, together with the 30 slides 7 and stepped brackets 25 connected thereto constitute a support for the carrying units 18 on which the coils are wound.

The shaft of cam 5 passes through the body 8 which is made hollow for the reception of slides

40 9 which are secured to and form a part of the slides 7. Springs 10 rest against the end of the members 9 and against the closed ends 11 of the body 8. Therefore, when the handle or lever 4 is turned up through substantially ninety degrees (90°), the cam 5 is turned into a horizontal position, and this permits the slides 7 to be forced inwardly by the springs 10. The slides 7 are provided adjacent their ends with brackets 12 and 13 for reception of the screws 14. These

45 screws are normally secured against endwise movement in the brackets but have screw-threaded connection with the slides 15, thus making it possible to adjust the vertical over-all dimension of the coils. However, when a set of 50 coils has been wound and it is desired to remove

them from the winding head, the lever 4 is turned upwardly, and this permits the two halves of the head to approach until the brackets 12 contact each other. It is then possible to remove the coils of wire from the individual winding spools 16, thus emptying the winding head in preparation for the winding of another set of coils. However, before this is started, the handle or lever 4 is lowered and the pin 17, or other suitable securing means, fastens the handle in place so that the coils, when wound on the head, will be exactly the same dimension as those previously wound. However, if it is necessary to change the size of the coils, this can be done by adjusting the screws 14 to adjust the slides 15 longitudinally of the screws. Each spool 16 is made up of two units which we may refer to as upper and lower units. These two units will next be described.

Body members, or wire-receiving units, 18 are grooved for the reception of triangular shaped webs 19 carried by guide members or carrying units 20, arranged to be adjusted relatively toward and from each other, as shown in Fig. 6, by means of a right and left hand threaded member 21, secured against movement longitudinally through the block 22, the location of which will be seen in Fig. 2. Guide members 20 are provided with holes 21a for the reception of screws 21, as seen in Figs. 10 and 11. The guide members 20 are provided along their lower edges with flanges 23, as indicated in Fig. 10, which serve as guiding means for the blocks or body members 18 when being adjusted toward and from each other. Each of the blocks 18 is grooved along one extremity, as indicated in Figs. 1, 2, and 6, to provide flanges 24 between which the wire may be wound.

The stepped block or bracket 25, shown in Fig. 12, is united by its edge 26 with a block or slide 15 and, therefore, as these slides move toward and from each other, the stepped blocks 25 also move toward and from each other, carrying with them the body members 18. This movement may be caused by turning cam 5 or screw 14. However, it is possible, by means of the screws 27, independently to adjust the spools 16 with relation to the blocks or brackets 25. This is by relatively adjusting the guide member 20 and the block 25, as best illustrated in Figs. 2 and 6. The screws 21 pass through blocks 22 and holes 21a in guide members 20. It is therefore clear that there can be no relative vertical movement between parts 18, 19, and 20. It is also clear that there can be no relative movement between blocks 22 and 20, although there may be movement between parts 20 and 25.

Holes 28 pass through the stepped blocks 25, from side to side, to allow for the requisite relative movement of the blocks 25 and the screw-threaded members 21 which are located in the holes 28. Screw-threaded holes 29 pass through the treads of the steps of the blocks 25 into the holes 28, as shown most clearly in Fig. 12. Therefore, since the screws 27 are held against longitudinal movement in the holes 30 of guide members 20 and have screw-threaded connection with blocks 25, the blocks 20 and 25 will be caused to have relative vertical movement with reference to each other when the screws 27 are turned. Hence, since blocks 25 are secured to or form a part of blocks 15 and can move only as the latter are moved, the assembly comprising 18, 19, 20, 21, and 22 must move relatively to blocks 25. This is for the purpose of independently adjust-

ing the size of the coils wound on the spools. The amount of this vertical adjustment, by adjustment of the screws 27, is not great, but a considerably larger adjustment can be secured by turning the screws 21 so as to increase or decrease the lateral width across the blocks 18 which, as stated above, slide on the flanges 23, as shown in Fig. 6.

All of the spools 16 are provided with screws 27 for adjusting the vertical dimension of each spool, except the smallest one 16a, the one at the left in Fig. 1, which is not provided with transverse adjusting means 21, as is clear from Fig. 1. As shown in Figs. 7, 8, and 9, this unit is constructed differently from the others. These end spools are denoted by the numeral 16a to distinguish them from the spools 16. Each comprises a block 31 and a cover plate 32, the two being held together by a screw or screws 33, passing through a hole or holes 34. This means is provided for drawing the block and cover plate together whereby to clamp the arcuate members 37 between them, the latter being slightly thicker than the space allowed for them between the cover plate 32 and the bottom of the groove in the block 31. Channels 35 are formed in the block 31, either inside or outside of the channels in which the arcuate members 37 travel. These are for the reception of the fingers 36 formed on the outside or inside of members 37, which fingers serve as stops to prevent members 37 from being withdrawn from the channels when being adjusted into position for adjusting the width of a coil formed thereon. Such position is shown at the left in Fig. 9. Normally the blocks 31 are formed integrally with the stepped blocks 25.

While Fig. 9 shows one way of constructing this unit, it is by no means the only way, as we have devised others for accomplishing the intended purpose, which is to permit adjustment of the size of a coil formed upon this unit. Likewise, other parts may be made differently than shown in these drawings without departing from the spirit of this invention as disclosed herein and as set forth in the appended claims.

Having now described our invention, we claim:

1. In a structure for the purpose stated, supporting means for slides, said supporting means being hollow and serving as a housing for springs, springs in said housing, slide members in said housing actuated toward each other by said springs, portions of said slide members being outside of said housing and sliding longitudinally thereof, operable means extending through said housing and having a cross-head located between the adjacent ends of said portions for causing longitudinal reciprocation thereof upon operation of said operable means, brackets carried by said portions and projecting approximately horizontally away therefrom, and wire receiving blocks adjustably carried by said brackets.

2. A single unit of a coil winding head comprising a pair of supporting bodies arranged in cooperative relation for the reception of wire being wound in a coil, said bodies being hollow for the reception of wire receiving members, the openings in said bodies being arcuate in form and the wire receiving members being of a size and shape to fit in the openings in said bodies and be movable into and partly withdrawable therefrom.

3. In a coil winding head, a substantially vertical support, a shaft extending therethrough and having a cross-head upon one side of the support

and means upon the opposite side of the support for rotating the shaft, motion limiting means for limiting the amount of rotation of the shaft, slides upon the same side of the support as the cross-head, the cross-head being normally in contact with adjacent ends of the slides, the slides being longitudinally movable by rotation of the shaft and cross-head, brackets supported by said slides, screw-threaded means between said slides and brackets for vertically adjusting the latter with relation to the former, whereby to make possible removal of coils from the head, wire receiving blocks carried by said brackets, and block adjusting means for adjusting the lateral width across the blocks whereby to adjust the size of coils wound thereon.

4. A wire supporting unit for a coil winding head comprising a block provided with arcuate grooves with their convex sides toward each other near the middle of the block, arcuate blocks slidable in said grooves, one end of each arcuate block having at its outer corners outwardly extending arms for the reception of a wire being formed into a coil, and a plate to be secured to the first mentioned block whereby to clamp the arcuate blocks in said grooves and hold them in adjusted positions.

5. A winding head adapted upon rotation to form coils of variable and predetermined length and width, and including: a pair of similar frames disposed on opposite sides of the axis of rotation of said head, said frame being adapted to be spaced apart a variable distance; at least

one pair of coil-receiving segments slidably mounted on each of said frames; a forwardly projecting web secured to each frame between the members of said pair of segments; an adjusting shaft rotatably mounted in an aperture, jointly traversing said web and said pair of segments, said shaft being anchored against longitudinal movement through said web and being provided with a slotted head and oppositely oriented threads upon its respective ends whereby rotation of said shaft causes the members of the pair of segments to move simultaneously and equidistant selectively toward or away from each other, said shaft being completely retractable within said segment aperture and being operable in such position by means of a slot-engaging instrument inserted within said aperture.

NOBLE E. MOORE.
GEORGE R. GILLGRASS.
